ATTORNEY.

UNITED STATES PATENT OFFICE.

HENRY SCHOTT, OF LONGMEADOW, MASSACHUSETTS.

REFRIGERATOR.

Application filed April 14, 1926. Serial No. 101,589.

My invention relates to improvements in refrigerators designed more especially for the reception of ice-cream packed in buckets or tubs, and the like, and carried on motor-driven delivery trucks, and resides essentially in a knockdown structure adapted to be assembled and set up within a housing constructed of insulating material or materials that prevent or retard the radiation of heat from the outside inwardly, which structure comprises certain peculiar, hollow, side, rear, and roof sections provided with means for attaching and fastening them together, to form an interior casing that is open in front beneath said roof section, said side and rear sections being further provided with tubular members which extend between the outer and inner side walls thereof and open into the chamber formed by said casing, and with drainage means at the bottom, together with a suitable, exterior housing, as aforesaid, that forms the bottom of said casing, is provided with a door to afford access to the open front of said casing, and with drainage means with which said first-named drainage means are in communication, a lid or cover, and such other parts and members as may be necessary or desirable in order to render the refrigerator as a whole complete and serviceable in every respect, all as hereinafter set forth.

The primary object of my invention is to produce an interior casing for a refrigerator, of the class described, which it is practicable to build and ship in compact and easily-handled sections, and then to be quickly set up within a suitable exterior housing, which latter may be erected on a truck, and to be readily fastened to said housing. The bottoms of the side and rear sections of the interior casing rest on the floor of the exterior housing, which floor also serves as the floor for the chamber in said casing.

The wood, cork, and other heat-insulating portions of the refrigerator as a whole can be built onto a truck in one place, and the metal portions thereof, which are the four sections hereinbefore referred to, can be constructed at some other place and shipped to the first place to be incorporated with the exterior structure to complete the refrigerator.

ator, which is an important advantage to the manufacturer of refrigerators of this type, and to the purchaser of the same as well. 55 Little or no skill is required in setting up the inner casing and fastening it to the outer casing.

The exterior structure or housing, of this refrigerator, may be constructed in its entirety apart from a truck and then placed on the chassis or floor thereof, or elsewhere as may be desired, or said housing may be built with the floor of the truck, to all intents and purposes, an integral part of the 65 housing. In the present example, the housing is represented as a structure entirely apart from and independent of the truck upon which it is to be mounted.

Another object is to provide a sectional, 70 interior casing which is comparatively light in weight, yet strong and durable, simple in construction, possesses superior refrigerating or cooling capacity, is comparatively inexpensive to manufacture, and, as previously intimated, the independent parts of which can be easily and quickly assembled, and readily secured in place within the exterior housing.

A further object is to provide the complete 80 refrigerator with space on top for the reception of empty buckets, tubs, or other objects.

Other objects and advantages will appear in the course of the following description. 85

I attain the objects and secure the advantages of my invention, by the means illustrated in the accompanying drawings, in which—

Figure 1 is a top plan of the interior casing of a refrigerator which embodies a practical form of my invention; Fig. 2, a top plan of said casing without the roof section; Fig. 3, a front elevation of said casing, with a portion of the left-hand side section broken away; Fig. 4, a front elevation of said roof section; Fig. 5, a longitudinal, vertical section through said roof section, taken on lines 4—4, looking in the direction of the associated arrow, in Fig. 1; Fig. 6, an inside 100 elevation of the rear section of said casing, said rear section having one corner broken away to show one of the drainage tubes; Fig. 7, an inside elevation of the right-

hand side section, having one corner broken away as in the preceding view, and, Fig. 8, an approximately central, vertical section through said casing and an exterior housing which together make up the complete refrigerator, said last-named section being taken from front to back.

Similar reference characters designate similar parts throughout the several views.

10 The interior casing of my refrigerator, which I will first describe, comprises two hollow side sections, a rear section, and a roof section, all preferably made of sheet-metal.

15 The side sections are alike, except that they are made in rights and lefts, and each comprises an outer wall 1, an inner wall 2 spaced from said outer wall, a bottom 3, and front and rear end walls 5 and 6, respectively. The bottom 3 and the walls 5 and 6 connect the wall 2 with the wall 1, and the latter extends some distance above the level of the tops of said walls 2 and 6, and some distance back of said wall 6, and such upwardly-extending part has at the ends inwardly-extending flanges 7 and 8, respectively, which flanges are top portions of said wall 5. The rearwardly-extending portion of the wall 1, back of the wall 6, may 20 project below the level of the tops of the walls 2, 5, and 6, as clearly shown at 9 in Fig. 7. The wall 6 is provided at the top on the outside with two hooks 10. There is an opening at some convenient point in the bottom 3, and set in such opening and projecting below said bottom is a drip tube 11, said tube being rigidly secured in place by any suitable means.

25 A compartment 12 for ice is formed in each side section, by the walls 1, 2, 5, and 6, and the bottom 3, of said section, and extending across such compartment are tubes 13. The compartment 12 is open at the top. The tubes 13 may be as numerous as is deemed necessary, and arranged or grouped in any appropriate manner. In the present example there are nine of these tubes arranged in three rows both vertically and horizontally. The tubes 13 are closed at 30 their outer ends and open at their inner ends, and they are set in suitable openings in the walls 1 and 2, and secured in place by any suitable means.

35 The rear section consists of front and back walls 14 and 15, respectively, end walls 16-16, and a bottom 17. The walls 16 and the end portions of the wall 14 are of the same height as are the walls 2, 5, and 6 of either side section, and such portions have 40 horizontal top edges 18-18 to receive the hooks 10 and afford supports for said hooks at their upper ends. In Fig. 7 a fragmentary section of the wall 14 is shown in supporting relationship to the hook 10 appearing 45 in said view. Between the horizontal,

top edge portions 18 of the wall 14, the top edge of said wall inclines upwardly to meet in the transverse, central, vertical plane of the rear section, and form an obtuse-angled support 19. The bottom 17 is provided at 70 some suitable point with a drip tube 11, as is the case with the bottom of either of the side sections. The walls 14, 15, and 16, and the bottom 17, form an open-top compartment 20 for ice; and there is here provided 75 a plurality of horizontal tubes 13, which tubes extend across said compartment, are closed at their outer ends and open at their inner ends, and similar in number and arrangement to the tubes 13 that extend across 80 the compartments 12 in the side sections. The wall 15 extends above the level of the tops of the walls 14 and 16 as high as the walls 1 of the side sections, and has at the ends above said walls 16 forwardly-extending 85 flanges 21-21.

The end walls 6 of the side sections and the front wall 14 of the rear section prevent communication between the chamber 20 and either chamber 12.

90 The roof section comprises a ridge-pole 22 and sloping plates 23 on both sides thereof, to form a gable roof, an end wall 24 having at the ends rearwardly-extending flanges 34, outer flanges 25 and 26, and inner flanges 27 and 28. The plates 23 are corrugated, as represented at 29, to afford a greater surface area for contact with the ice, and, therefore, an increased cooling area. There are two flanges 25 which depend from opposite side 95 edges of the plates 23, and the same number of flanges 27 which depend from said edges, and two flanges 26 which depend from the back edges of said plates, and the same number of flanges 28 which also depend from 100 said last-named edges. The upper-edge portions of the walls 2 of the side sections are receivable between the flanges 25 and 27, and the angular support 19 of the wall 17 of the rear section is receivable between the 105 flanges 26 and 28, the angle of said support corresponding with the angle which the roof plates form with each other. The wall 24 extends upwardly from the front edges of the plates 23 to a height which brings the 110 top of the same on a level with the tops of the walls 1 and 15 when the sections are assembled.

115 Bolts 30 and nuts 31 may be provided to secure the flanges 25 and 27 to the walls 2 adjacent to the rear ends of said walls, and to secure the flanges 26 and 28 to the wall 14 adjacent to the horizontal supporting parts 18 thereof, holes being provided for these bolts in said flanges, two of the flange holes appearing at 32-32 in Fig. 4, and certain of the wall holes appearing at 33 in Figs. 6 and 7.

120 The sections just described are assembled by setting up the rear section, passing the 130

hook 10 at the rear end of the right-hand side section down over the right-hand supporting part 18 and the hook 10 at the rear end of the left-hand section down over the 5 left-hand supporting part 18, of the wall 14, with the side-section flanges 8 inside of the rear-section flanges 21, and forcing the two side sections down until their bottoms 3 rest with the bottom 17 of said rear section on 10 the floor, placing the roof section on top of the side-section walls 2 and said wall 14 and forcing it down into place with the upper edges of said walls between the roof-section flanges, in the manner explained above, and 15 with the side-section flanges 7 outside of the roof wall 24 and the flanges 34 at the ends of said last-named wall inside of the side-section walls 1. The assembled sections thus make up a casing within which is a 20 chamber 35 that is open in front. The chamber 35 is for the reception of buckets or tubs of ice-cream. The tubes 13 all open into the chamber 35. The roof plates 23 are located well below the upper edges of 25 the several outside walls of the casing, thus leaving a chamber 36 for the ice, which chamber opens through the top, and opens below, around the side and rear edges of the roof, into the compartments 12 and 20. 30 Ample space is thus provided for ice. The ice, being on the top and three sides of the chamber 25, cools the corrugated roof plates 23, the side-section walls 2 and rear-section wall 14, and the pipes 13. Cooled surfaces 35 adequate for keeping cool the contents of the chamber 25 are thus afforded.

The interior casing is set up in an exterior housing such as that illustrated in Fig. 8. This housing comprises exterior wood sheathing 37 on the bottom and four sides, and an interior cork filling 38 also on the bottom and four sides, with paper 39 between said sheathing and filling, and inside of said filling, wood sheathing 40 on top of the uppermost layer of paper on the floor of the housing, and a lid or cover 41. The sides of the exterior sheathing 37 extend some distance above the top of the sides of the filling 38, and the cover 41 is adapted to rest on the upper edges of said filling inside of the upwardly-extending portions of said sheathing. There is a sheet-metal flashing 42 between the cover 41 and the filling 38 and sheathing 37 at the top. A receptacle 43 is provided, above the cover 41 and between the upwardly-extending portions of the sheathing 37, in which may be placed empty buckets or tubs or other objects, and which affords room and repairing means for the cover 41 in the event the chamber 36 be filled with ice above the level of the ledge formed by the top edges of the filling 38. The cover 41 may be provided with handles, as 44—44. The housing has an opening in the front side thereof to

afford access to the chamber 35, and a suitable door, as 45, of usual and ordinary construction, is provided for such opening.

Nails, as 46, are employed to secure the casing to the housing, and there are openings 47 in certain of the housing members for the reception of such nails, there being two of such openings in the upper part of each side-section wall 1 at and adjacent to the ends thereof, one in each of the two flanges 7 and each of the two flanges 8 near the upper edge thereof, two in the rear-section wall 15 near the top and adjacent to the ends thereof, one in each flange 21 near the top thereof, two in the roof-section wall 24 near the top and adjacent to the ends thereof, and one in each of the flanges 34 near the top thereof. It follows, therefore, that the rear-section wall 15, and with it the side-section flanges 8, are secured by two nails 46 to the back side of the housing; each side-section wall 1, with the contiguous rear-section flange 21 and roof-section flange 34, is secured by two nails 46 to the corresponding side of said housing; and the roof-section wall 24, with the side-section flanges 7, is secured by two nails 46 to the front side of said housing. A filling strip 49 is inserted between the wall 24 and flanges 7 and the front side of the housing, and the nails 46 which pass through the holes 47 in said wall and flanges also pass through said strip.

The floor of the housing is provided with drip pipes 48 which correspond in number with the drip pipes 11, are larger than the latter, and located in position to receive them when the casing is set up in the housing. The water from the ice as it melts escapes from the chambers 12 and 20 through the pipes 11 and 48.

The manner of filling the ice compartments, and that of utilizing the chamber 35, will be clearly understood from the foregoing, as will also the way in which the receptacle 43 is or may be used.

More or less change in the shape, size, construction, and arrangement of some or all of the parts of this refrigerator, in addition to those hereinbefore pointed out, may be made without departing from the spirit of my invention, or exceeding the scope of what is claimed.

What I claim as my invention, and desire to secure by Letters Patent, is—

1. An interior casing, of a refrigerator, comprising hollow side and rear sections and a roof section provided with attaching means whereby the same are held together to form the top and three sides of a cooling chamber, and tubular members extending transversely of said side and rear sections, opening at their inner ends into said chamber, and closed at their outer ends.

2. An interior casing, of a refrigerator,

- comprising hollow side and rear sections, said side sections being provided at their rear ends with hooks to engage the front wall of said rear section, and a roof section 5 adapted to be mounted on and attached to said side and rear sections.
3. An interior casing, of a refrigerator, comprising hollow side sections, a hollow rear section adapted to be attached to the 10 rear ends of said side sections, and a roof section provided underneath on the sides and at the rear end with outer and inner flanges spaced apart to receive between them and engage upper-edge portions of the inner 15 walls of said side and rear sections.
4. An interior casing, of a refrigerator, comprising hollow side sections the outer walls of which rise above the level of the inner walls, a hollow rear section adapted to be attached to the rear ends of said side sections, and the outer wall of which rear section rises above the inner wall, and a roof section provided underneath at the side and rear edges with outer and inner flanges to 20 receive between them and engage upper-edge portions of the inner walls of said side and rear sections, and having at the front end an upwardly-extending wall to assist in forming, with the upper portions of the 25 outer walls of said side and rear sections, a compartment.
5. In an interior casing, of a refrigerator, hollow side sections, a hollow rear section adapted to be attached to the rear ends of 30 said side sections, the intermediate portion of the front wall of said rear section at the top forming an angular support, and a roof section of gable type provided at the rear edges with outer and inner flanges adapted 35 to receive between them said angular support.
6. In an interior casing, of a refrigerator, hollow side sections provided at their rear ends with hooks, a hollow rear section having parts of its front wall at the top adapted 40 to receive said hooks, and the intermediate portion of said wall at the top forming an angular support, and a roof section of gable type provided at the rear edges with 45 outer and inner flanges adapted to receive between them said angular support.
7. In an interior casing, of a refrigerator, hollow side sections provided at their rear ends with hooks, a hollow rear section having parts of its front wall at the top adapted 50 to receive said hooks, and the intermediate portion of said wall at the top forming an angular support, and a roof section of gable type provided at the side and rear edges 55 with outer and inner flanges adapted to receive between them upper-edge portions of the inner walls of said side sections and said angular support.
8. In an interior casing, of a refrigerator, hollow side sections, a hollow rear section 60
- adapted to be attached to the rear ends of said side sections, a roof section provided underneath at the side and rear edges with outer and inner flanges spaced apart to receive between them and engage upper edge 70 portions of the inner walls of said side and rear sections, and means to secure said flanges to said walls.
9. An interior casing, of a refrigerator, comprising hollow side and rear sections and a roof section adapted to be fastened together to form the top and three sides of a cooling chamber, the outer walls of said side and rear sections extending above the level of the roof of said roof section, and the latter having at the front end a part which extends above said level, whereby an ice compartment is formed above said roof, which compartment opens below into the compartments in said side and rear sections. 75
10. An interior casing, of a refrigerator, comprising hollow side and rear sections and a roof section adapted to be fastened together, with the rear ends of said side sections abutting said rear section, and said roof section resting on the inner walls of said side and rear sections, the outer walls of said side and rear sections rising above the level of the roof of said roof section, and having flanges at their ends, and said roof section having at its front end a wall which rises above said level. 80
11. An interior casing, of a refrigerator, comprising hollow side and rear sections and a roof section adapted to be fastened together, with the rear ends of said side sections abutting said rear section, and said roof section resting on the inner walls of said side and rear sections, the outer walls of said side and rear sections rising above 90 the level of the roof of said roof section, and having flanges at their ends, and said roof section having at its front end a wall which rises above said level. 95
12. The combination, in a refrigerator, with a housing comprising heat-insulating walls and a heat-insulating floor, and having a door in one of said walls, the outer portions of said walls extending above the inner portions thereof to form a receptacle, and a removable cover adapted to rest on the upper edges of said inner portions, of an interior casing comprising hollow side and rear sections and a roof section attached together within said housing, and forming the top and three sides of a cooling chamber which opens behind said door, ice compartments in said side and rear sections, and an ice compartment above the roof of said roof section, which last-named compartment 105
- 130

opens into the compartments below, said roof section being removable and having at the front end an upwardly extending wall that assists in forming the front side of said 5 second-named compartment.

13. The combination, in a refrigerator, with an exterior housing comprising heat-insulating walls and a heat-insulating floor, one of said walls having a door therein, and 10 the outer portions of said walls extending above the inner portions thereof to form a receptacle, a lid adapted to rest on the upper edges of said inner portions, and drain pipes extending through said floor, of an 15 interior casing comprising hollow side sections provided with hooks at their rear ends, a hollow rear section having portions of the inner wall thereof adapted to be engaged by said hooks, the outer walls of said sections extending above the end walls thereof 20 and nailed to the walls of said housing, a roof section having at the front end a wall which is nailed to the adjacent wall of said housing, and having at the sides and rear

ends flanges adapted to receive between the 25 upper-edge portions of the inner walls of said side sections, and the intermediate portion of the inner wall of said rear section, bolts to secure said flanges to said side- and rear-section inner walls, and drain pipes in 30 the bottoms of said side and rear sections to communicate with said first-named pipes.

14. The combination, in a refrigerator, with an exterior heat-insulating housing having a ledge around the inside of the 35 walls thereof, which ledge is somewhat remote from the uppermost edge of said walls, and also having a door, and a removable cover adapted to rest on said ledge, whereby is formed a receptacle above said cover, of 40 an interior casing forming the top and three sides of a cooling chamber which opens behind said door, and having therein ice compartments on said three sides, and an ice compartment between said top and said 45 cover.

HENRY SCHOTT.
